UNITED STATES PATENT OFFICE.

LEWIS PENGILLY, OF STOCKTON, CALIFORNIA.

DESIGN FOR A COMBINATION CIGARETTE HOLDER, DISPENSER, AND LIGHTER.

Application filed December 8, 1923. Serial No. 7,978. Term of patent 14 years.

To all whom it may concern:

Be it known that I, LEWIS PENGILLY, a citizen of the United States, residing at Stockton, in the county of San Joaquin and State of California, have invented a new, original, and ornamental Design for a Combination Cigarette Holder, Dispenser, and Lighter, of which the following is a specification, reference being had to the accompanying drawing, forming part thereof.

The figure on the drawing is a perspective view of a combination cigarette holder, dispenser, and lighter, showing my new design.

I claim:—

The ornamental design for a combination cigarette holder, dispenser, and lighter, as shown.

LEWIS PENGILLY.
